LIFE SAVING FLOTATION DEVICE

Robert J. Fraebel, Red Bank, and Elsie K. Irre, Manasquan, N. J., assignors to The Garrett Corporation, Los Angeles, Calif., a corporation of California

Application April 3, 1956, Serial No. 575,811

4 Claims. (Cl. 9—17)

This invention relates to a life-saving flotation device and especially a device of that type designed for use by persons whose activities require that they be prepared to descend by parachute from aircraft.

Its chief objects are to provide a device of this character which, in contemplation of being put to use, can be worn, with its buoyancy elements collapsed and enclosed in packs, without excessive interference with the activities of the wearer; to provide specific factors of safety, especially in the use of such a device by a wearer who also must wear a parachute assembly comprising body-engaging straps or "harness" required to withstand the strains incident to the opening of the parachute and requiring to be freed from the person's body and from the flotation device in the discarding of the parachute; to provide against discomfort or injury of the wearer in his being towed in the water; and to provide more detailed advantages that will be manifest from the following description.

For attaining these objects our device, among other features, preferably comprises two individually inflatable cells adapted to be worn in packed condition at or slightly below the respective armpits of the wearer, but, when inflated, to be quickly connected to each other at their front ends, after parachute straps or the like have been passed outward between them, to provide a chin-supporting buoyancy structure at the front of the device. Each of the cells preferably is of arcuately curved shape, with substantial predominant buoyancy in its upper-front and upper-rear portions, so that the center of buoyancy of the cells, for stability, is high in the structure because of the relatively large front and rear portions of the cells as compared with their relatively low middle portions. Thus their center of buoyancy is high above and slightly forward of the center of gravity of the wearer and his equipment, assuming him to be in a standing position, for proper attitude of the wearer in the water, whether he is conscious or unconscious.

Of the accompanying drawings:

Fig. 1 is a front elevation of the wearer and the flotation device in position, with the cells collapsed and packed.

Fig. 2 is an elevation of the same from the left of Fig. 1, the near arm of the wearer being shown in broken or phantom lines for clearness of illustration.

Fig. 3 is a rear elevation of the same.

Fig. 4 is a front elevation of the same with the cells inflated and their front ends connected, as in their condition of service in the water, but with the wearer in a standing position for clearness of illustration.

Fig. 5 is an elevation of the same from the right of Fig. 4.

Fig. 6 is a rear elevation of the same.

Fig. 7 is a larger scale detail of parts as shown in Fig. 4.

Fig. 8 is a fragmentary elevation, on a large scale, showing the same one of the packs that is presented in Fig. 2.

Fig. 9 is a corresponding elevation from the body-engagement side of the same pack.

Fig. 10 is a fragmentary front elevation of the front end of a cell showing a preferred shape of its end wall.

Fig. 11 is a plan view of rear portions of a pair of cells secured to each other in accordance with a modification.

Referring first to Figs. 4 to 7, where the parts are shown in functioning condition, the device comprises two inflatable, air-tight fabric cells, 10 and 11, each of arcuately curved shape and each secured, by means of an attachment flange such as the flange 11^a, Fig. 5. In the middle region of its inner, upwardly extending margin, each attachment flange is secured by pull-tab snap-fasteners, 11^b, 11^c, or simply by sewing, to the middle portion of the rectangular, body-contacting, base wall, 11^c, of a four-flap, box-like, fabric, pack container, which will be further described later with reference to Figs. 8 and 9, in which one of the packs is shown more in detail.

The harness for holding buoyancy members, either packed or inflated, in relation to the body of the wearer, comprises a belt-like strap 12 which slidably extends between the above mentioned base wall of the pack container and a pair of retaining or guideway-defining straps 13, 13^a, Fig. 9, extending crosswise of the belt strap and sewed, at each side of the latter, to the body-contacting face of the container's base wall 11^c. The belt strap is provided at the front of the wearer with a quick-detachable and adjusting buckle assembly 12^a.

The said harness comprises also a pair of shoulder straps 14, 15, each of which, at the rear part of the pack, has its end portion extending across the guideway strap 13 and the underlying belt strap 12, Fig. 9, and sewed to the base wall of the pack container at the respective sides of the belt strap.

At the shoulder-blade position, as shown in Fig. 3, the shoulder straps are crossed and slidably extend through slots in a fabric retaining and positioning pad 16. From that position they extend forward over the shoulders of the wearer and then downward to, and are engaged in, respective loops such as the loop 13^m, Figs. 2 and 9, which are provided by looped-back and sewed upper end portions of the forward, vertical, guideway straps 13^a, Fig. 8.

The harness as thus described serves to hold the cells, in either packed or inflated condition, in the general positions in relation to the wearer's body in which they are shown in the drawings, and their high centers of buoyancy give further stability of their relative positions when they are in service in the water.

Still further stability, and dependable support for the chin of the wearer, are provided by quickly engageable means for holding the front ends of the cells in abutted relation to each other and preferably by providing the cells with front end-walls, such as the wall 10^a, Fig. 10, adapted to be held flattened against each other by such holding means, as in Fig. 4. Such a wall is provided preferably by a flat piece of fabric, adapted to be bulged to only a large-radius spheroidal shape by the inflation. Slight tapering of the cell toward and to such an end-wall, and the stiffness against buckling that is provided by its surrounding taped seam 10^b, also contribute to the long-radius character of its bulge.

The means here shown for holding the cells' front ends flattened against each other comprises, Fig. 4, a snap 11^d suitably mounted upon the front end portion of the cell 11 at the latter's highest part and a snap 11^e likewise mounted but well below the middle of that part of the cell, the snaps being adapted to be engaged in respective D rings 10^d and 10^e each connected to the cell 10 through adjusting buckles 10^r and 10^s and adjustable straps 10^t and 10^u.

The lower snap 11^e, being less accessible for easy manipulation than the upper snap 11^d, preferably is positively held in fixed position on the cell by a holding strap 11^x extending through the hook portion of the snap and having its ends, on opposite sides of the snap, sewed to the anchor patch of the snap, as is shown with regard to the nearer of its ends in Fig. 4.

In the case of the wearer being towed in the water, by a wind-blown parachute or for rescue, face up or face down, and by the feet or by the hands, or otherwise, it is desirable that there be provision against excessive backward bending of his neck by the resistance of the water and against such shifting of the position of the buoyancy structure in relation to his body as would result in an undesirable or dangerous positioning of the center of buoyancy in relation to the center of gravity and/or the center of application of the pulling force.

Such provision is afforded by a neck strap 10^x, Figs. 4, 5 and 6, having one of its ends anchored to the left cell at the same position as the anchorage of the snap 11^d, and engaged near its other end in an adjusting buckle 10^y, Fig. 4, secured to the base of a snap 10^z which is adapted to be engaged in a D-ring 10^w which is interlinked with a looped-back and sewed anchorage end portion of the strap 10^p. The strap 10^x, adapted to be passed around the neck and snapped to the D-ring after the cells have been inflated and their front ends connected, provides a direct connection from the back of the wearer's neck to the top of the front portion of the buoyancy structure and thus performs the functions above indicated.

In case of the wearer inadvertently or otherwise inflating the cells before reaching the water and then hitting the water head first, the neck strap, if then quickly put in functioning relationship, prevents such deformation of the cells or displacement of their front lobes by impact with the water as would shift the center of buoyancy so far away from his head as to be dangerous.

The right-hand pack container, for illustration as to both of them, is of box-like shape, comprising the body-contacting, harness-anchoring base wall 11^c above referred to; "edge" walls 11^f, 11^g, 11^h, 11ⁱ, Figs. 8, 9, 1 and 2, secured to the base wall by sewing and by rivets 11^j, 11^k; and four generally triangular closure flaps 17, 18, 19 and 20 which are adapted to be held in their pack-closing positions by a heavy-cord loop member 21 mounted upon the innermost flap member 17, extending through holes in the three other flap members, and adapted to be releasably held in flap holding relationship by a pull cotter 22.

An inflating cylinder 23 has its mounting upon and is in communication with the cell 10 at 24. A pull cord 25 from its control lever 26, and a pull cord 27 from the pull cotter 21, extend to and are connected to a single pull-knob 28, with more slack maintained in the cord 25 than in the cord 27, when the cell is in packed condition, by a tunnel-defining covering strip 29, Fig. 8, overlying the cords and have only parts of its margins sewed to the flap 20, so that the cords both extend downwardly and outwardly from the "tunnel" at a forward, lower, corner position where an outlet for the cord 25 is provided by absence of sewing of the cover strip 29 to the flap 20.

The cord 27 extends outward between the overlapped margins of the flap 20 and the flap 19. Because of the reach 27^a of sewing of the strip 29 to the flap 20, even a straight downward pull of the knob 28 causes first the release of the flaps and then opening of the valve of the inflating cylinder, so that inflation of the cell causes it to emerge from the pack and take its rocker-like shape and its functioning position in relation to the wearer.

Absence of sewing of the cover strip 29 to the flap 20 at the rear part of the lower margin permits a corner

portion 29^a of the cover strip to be turned back as in Fig. 8 to provide access for manipulation of the loop 21 and the cotter 22 in the packing of the cell.

For ease of retaining the collapsed and folded cell in proper position while the flaps are being closed and fastened in the packing operation, and for assuring the placing of the flaps in proper sequence, the flaps can be sewed to one another for a short distance from each corner of the pack, as at 18^a, 19^a, 20^a, Fig. 8.

The mode of operation and the advantages of the device are adequately brought out in the foregoing description.

In the embodiment above described the cells 10 and 11 have no connection of their rear lobes directly to each other (Fig. 6), but in some types of use they can be so connected. In Fig. 11, for example, the rear lobes are shown as being connected, at about their highest parts, by a fabric tie strip 30 having at its ends portions sewed to respective anchor patches 30^a and 30^b which are cemented to the respective cells.

Other modifications are possible without departure from the scope of the invention as defined by the appended claims.

We claim:

1. A unitary life-saving flotation device comprising a harness for removably retaining said device on the body of a wearer, said harness including torso encircling means attachable to pass beneath the respective armpits of the wearer, a pair of pack containers supported respectively on opposite sides of said torso encircling means to position said pack containers beneath the respective armpits of the wearer, an inflatable buoyancy element releasably packed in each of said pack containers, each of said buoyancy elements when inflated having an elongated hollow arcuately curved shape, each buoyancy element being connected to its pack container generally mid-way of the length of said arcuately curved shape with the forward and rearward end portions of said elements extending upwardly respectively in front of and behind the shoulders of the wearer in the inflated state, said forward end portions of said buoyancy elements having cooperating wall sections engageable to form the adjoining wall sections of said buoyancy elements in a chin supporting buoyancy structure, and securing means on said forward end portions of said buoyancy elements for detachably retaining said wall sections in engagement.

2. A unitary life-saving flotation device as recited in claim 1 and further including a neck strap connectable to said chin supporting structure and adapted to extend about the neck of the wearer for holding said chin supporting structure adjacent the chin of the wearer.

3. A unitary life-saving flotation device as recited in claim 1 wherein each of said pack containers is formed of flexible sheet material having a body engaging base wall and a plurality of flaps connected to the margins of said base wall, a loop element mounted upon one of the flaps for extending through an aperture in at least one other of the flaps, and a pull-cotter insertable in a part of said loop element projecting beyond said aperture.

4. A unitary life-saving flotation device comprising a harness for removably retaining said device on the body of a wearer, said harness including a belt firmly engageable around the torso to pass beneath the respective armpits of the wearer and shoulder strap means connected to retain said belt in position on the wearer, a pair of elongated hollow arcuately curved inflatable buoyancy elements supported respectively on opposite sides of said belt, each of said buoyancy elements being connected to said belt generally mid-way of its length to dispose the mid-portions of said elements at positions adjacent the respective armpits of the wearer with the forward and rearward end portions of said elements extending freely upwardly from said belt respectively in front of and behind the shoulders of the wearer, said

forward end portions of said buoyancy elements having cooperating wall sections engageable to form the adjoining wall sections of said buoyancy elements in a chin supporting buoyancy structure, and securing means on said forward end portions of said buoyancy elements for 5 detachably retaining said wall sections in engagement.
